CLAIM

The ornamental design for a push-switch with a cord, as shown and described.

DESCRIPTION

FIG. 1 is a top plan view of a push-switch with a cord showing my new design;

FIG. 2 is a bottom plan view thereof;

FIG. 3 is a front view thereof;

FIG. 4 is a rear view thereof;

FIG. 5 is a left side view thereof;

FIG. 6 is a right side view thereof; and,

FIG. 7 is a magnified cross sectional view taken along line 7—7 in FIG. 1, wherein an inner structure of the push-switch with a cord is omitted.
